[57] CLAIM

The ornamental design for a valve handle, as shown and described.

DESCRIPTION

FIG. 1 is a perspective view of a valve handle showing our new design;

FIG. 2 is a side view thereof, the opposite side being a mirror image of the side shown;

FIG. 3 is a top plan view thereof; and,

FIG. 4 is an end view, the opposite side being a mirror image thereof.

The broken line showing is for illustrative purposes only and forms no part of the claimed design.
